UNITED STATES PATENT OFFICE.

ERNEST DELACUVELLERIE, OF DAMPREMY, BELGIUM, ASSIGNOR TO THE SOCIETE ANONYME "BREVETS FOURCAULT," OF DAMPREMY, BELGIUM, A CORPORATION OF BELGIUM.

ARRANGEMENT FOR CONTROLLING OR REGULATING THE THICKNESS OF SHEET GLASS OBTAINED BY VERTICAL DRAWING.

Application filed April 16, 1923, Serial No. 632,499. Renewed July 25, 1925.

To all whom it may concern:

Be it known that I, ERNEST DELACUVELLERIE, engineer, subject of the King of Belgium, residing at Dampremy, in Belgium, and having post-office address Usines de Dampremy, in the said city, have invented certain new and useful Improvements in the Arrangements for Controlling or Regulating the Thickness of Sheet Glass Obtained by Vertical Drawing; and I do hereby declare the following to be a full, clear, and exact description of the invention, such as will enable others skilled in the art to which it appertains to make and use the same.

The present invention relates to a method for use in the mechanical manufacture of sheet glass by vertical drawing through a die or piece of refractory material; its object consists essentially in a particular form of die piece which allows of sheets of an absolutely constant thickness being manufactured, this naturally being an essential condition in order to ensure efficient working during manufacture.

As is known, it often happens that the part of the glass sheet nearest the walls of the furnace may be less efficiently supplied with liquid glass than the parts of the glass sheet more distant from the said walls. By the present invention these difficulties are completely overcome. In order to obtain the desired result it is necessary therefore to facilitate the passage of the liquid glass through the die piece of refractory material which controls the supply and more particularly for the parts of the glass sheet nearest the walls of the furnace and generally towards the edges thereof.

The accompanying Figures 1 to 11 will permit of the description of the improvement relevant to the refractory die piece above referred to being readily understood. In these figures:

Figures 1 to 4 shewn by way of comparison, relate to the die piece in question such as actually in use.

Figures 5 to 11 shew the improvement in accordance with the present invention.

Figure 1 is a plan view of the improved die piece actually in use.

Figure 2 is a cross section on the line 2—2, Figure 1.

Figure 3 is a cross-section on the line 3—3, Figure 1.

Figure 4 is a longitudinal section on the line 4—4, Figure 1.

Figure 5 is an inverted plan view of a die piece in accordance with the present invention.

Figure 6 is a cross-section on the line 6—6, Figure 5.

Figure 7 is a section on the line 7—7, Figure 5.

Figure 8 is a longitudinal section on the line 8—8, Figure 5.

Figure 9 is a longitudinal section of a part of the furnace on the line 9—9, Figure 10.

Figure 10 is a sectional plan on the line 10—10, Figure 9.

Figure 11 is a cross section on the line 11—11, Figure 10.

In Figures 1, 2, 3 and 4 shewing a die piece, it will be seen that these die pieces are formed of an extended block provided with a longitudinally arranged slot or recess *d d e e* the width of which varies with the horizontal section as clearly indicated in the longitudinal and cross sectional views in Figures 2, 3 and 4. The slot or recess obtained by reason of this variation in section is limited by two plane or convex walls. The cross section of the slot or recess is the same from the centre to the extremities as shewn by Figures 2 and 3.

In an apparatus of this type the glass which, entering into the slot or recess through the section *e e* must escape through the section *d d*, obviously encounters in its vertical ascending movement through the die piece a certain resistance due to friction against the walls.

For the efficient working of the method of drawing, it is absolutely necessary that this resistance be constant throughout the length of the slot or recess in the refractory die piece. In order that this result may be obtained of the die piece formed as above stated, it is evident that the glass ought to be of the same degree of viscosity throughout. Unfortunately this is not the case as will be readily understood on referring to Figures 9, 10 and 11 where several die blocks are indicated in the tank of cast glass. In

these figures the drawing machines are indicated at *f*, *m* and *a*, the reheating chambers for the cast glass at *b* and *p* indicates the bridge pieces immersed in the glass which render the chambers *b* separate or independent of the working spaces *a*; *c* are the outlets for the flames which are intended to reheat the cast glass at *b*. The indices 2 and 3 are added to the reference letters for the corresponding parts of the other spaces. The temperature of the glass along the walls of the furnace is naturally lower than that in the centre and it follows that the sheet *f* by reason of the constancy of the form of the slot in the refractory die pieces through which it passes and which is referred to above, is not drawn in a uniform manner throughout its width since the viscosity varies at different points of this width.

20 The improved form of refractory die piece in accordance with the present invention has been designed with a view of avoiding this defect. It may be advantageously remarked that the foregoing applied only to the form of the slot or recess in the part marked *e e* and to the surfaces *e e* which join these parts with *d d*; the form itself of the section *d d* not being under consideration because it is supposed to be determined by other considerations than those which are here mentioned.

25 The arrangements conforming to the present invention are indicated in Figures 5, 6, 7 and 8. They have been designed with a view of reducing the friction of the glass along the walls in proportion as one recedes from the middle of the die piece towards the edges. Figure 5 shews the refractory die pieces from below, that is to say, looking on the surface which is immersed in a bath 30 of glass.

It shews the section of the slot or recess of the die piece in the plane of the base. This section *e' e'* is narrowed or restricted at the middle and enlarged or extended at 35 its ends where it extends beyond the length of the upper slot *d'*.

Figure 6 shews a cross section through the middle of the die piece. It will be seen therefrom that the section is approximately

the same as that of the die pieces usually employed and described above with reference to Figure 3.

But in proportion as the cross sections considered extend from the centre of the die piece, the width of the opening *e'* increases and its junction with the slot *d'* becomes an irregular awkward surface. At the same time the section of the slot or recess is curved inwardly and upwardly in such manner as to increase in this region the volume of glass imprisoned (see cross section Figure 7); at the ends a similar inward curve is formed by a half surface of revolution *n n* having the vertical axis passing through the end of the slot *d' d'*, this surface joining the main incurving surface.

The features of this form being fully understood, it will be readily perceived that the friction of the glass along the walls of the die piece in the interior of the slot or recess diminishes gradually towards the ends. This reduction of the friction, combined with the increase in the viscosity of the glass which is a necessary condition, has for its result to permit of the cast glass escaping at all points of the slot *d' d'* with equal facility, thus completely correcting the defect of actual die pieces hereinbefore indicated.

I claim:

1. A die piece for sheet glass manufacture consisting of a body having a slot thereon for the escape of glass during drawing, the lower portion of said slot varying in width from the center to the ends thereof.

2. A die piece as claimed in claim 1, characterized in that width of the lower portion of said slot gradually increases on each side of the center outwardly to the ends thereof.

3. A die piece as claimed in claim 1, characterized in that the width of the lower portion of said slot gradually increases on each side of the center outwardly towards the ends thereof, and the width of the slot being increased in a symmetrical manner with respect to the axis of the piece.

In testimony whereof I have signed my name to this specification.

ERNEST DELACUVELLERIE.
